FORK OR SIMILAR ARTICLE OF FLATWARE

Robert L. Doerfler, Meriden, Conn., assignor to The International Silver Company, Meriden, Conn., a corporation of Connecticut

Filed July 28, 1960, Ser. No. 61,558

Term of patent 14 years

(Cl. D54—12)

FIG. 1.

FIG. 2.

FIG. 3.

FIG. 4.

FIG. 5.

Fig. 1 is a front elevational view of a fork, showing the essential features of my design in full lines;

Fig. 2 is a rear elevational view;

Fig. 3 is a side elevational view;

Fig. 4 is an enlarged cross sectional view taken on the line 4—4 of Fig. 1; and

Fig. 5 is an enlarged cross sectional view taken on the line 5—5 of Fig. 1.

The back of the fork handle is substantially plain as shown in Figs. 2, 4 and 5.

The design is intended for use on sets comprising forks, spoons, knives and similar articles of flatware.

I claim:

The ornamental design for a fork or similar article of flatware, substantially as shown and described.
